UNITED STATES PATENT OFFICE.

JULIUS H. BITTERLICH, OF NEW HAVEN, CONNECTICUT.

MACHINE FOR MAKING AND COVERING PAPER BOXES.

SPECIFICATION forming part of Letters Patent No. 417,533, dated December 17, 1889.

Application filed August 4, 1888. Serial No. 281,949. (No model.)

To all whom it may concern:

Be it known that I, JULIUS H. BITTERLICH, residing at New Haven, in the county of New Haven and State of Connecticut, have 5 invented certain new and useful Improvements in Machines for Making and Covering Paper Boxes; and I do declare the following to be a full, clear, and exact description of the same, reference being had to the accompanying drawings, which form a part of this specification.

My invention relates to an improved machine for making paper boxes, and particularly air-tight boxes, in which the box-body and the box-cover are of about equal depth, the object being to secure economy of space, effect a saving of labor by securing the highest convenience and facility for all of the operations incident to the work, avoid waste 20 of material, and attain a high degree of perfection in the product by a superior application of the adhesives and a perfect tempering of the paper in its moistened state.

With these ends in view my invention consists in an apparatus adapted to be suspended above the work-table upon which the manual parts of the work are carried on; in long horizontal steam-heated troughs for the adhesives; in movable frames and distributing- 30 drums located in such troughs; in means for controlling the stock-strip in its relation to such drums and as to the amount of adhesive material applied to it; in a novel box-former; in a novel strip measurer and cutter, and in certain details of construction and combinations of parts, as will be hereinafter described, and pointed out in the claims.

In the accompanying drawings, Figure 1 is a view in end elevation of an apparatus embodying my invention and showing its adaptation to forming box-bodies or box-covers. Fig. 2 is a similar reverse view showing the adaptation of the apparatus for covering such bodies or covers. Fig. 3 is a side view 45 of the apparatus looking at the box-former. Fig. 4 is a similar view from the opposite side of the apparatus and looking at the measuring and covering attachments thereto. Fig. 5 is an enlarged detached sectional view of 50 one of the troughs, and showing also one of the distributing-drums and one of the strip-controllers. Fig. 6 is a detached perspective

view of one of the drum-frames and drum. Fig. 7 is a detached plan view of one of the strip-controllers. Fig. 8 is a broken detached 55 sectional view of the box-former and its spindle and standard. Fig. 9 is a view of the box-former in end elevation. Fig. 10 is a view of the former in transverse section with its parts separated. Fig. 11 is a view showing the 60 parts of the former separated on the diagonal line *a b* of the preceding figure into two groups and laid side by side. Fig. 12 is an enlarged detached view, in vertical section, through one of the stock-rolls, and showing 65 the tapering plug in its either end. Fig. 13 is an enlarged detached view, partly in plan and partly in section on the line *c d* of Fig. 4, of the cutting-off shears; and Fig. 14 is a plan view of the manual roller employed to 70 develop the corners of the green forms when the same are on the former.

As herein shown, two long horizontal troughs *A* and *B*, each having an isolated steam-chamber *C* and respectively located 75 one above the other, are suspended over and throughout the length of the long work-table *D*, whereon the manual parts of the work are performed by operatives who stand on its opposite sides. Glue, sizing, or other adhesive 80 material is supplied to one end of each trough by suitable pipes *E*, having faucets *F F*, and connected to reservoirs *G G*, preferably located in the room above, where the material is cooked and prepared. The opposite ends 85 of the troughs have faucets *H H*, for drawing them off. The steam-chamber *C* of each trough is connected at one end with a steam-pipe *I*, having valves *J J*, and provided at the other end with steam-discharge connections *K K*, as shown. The suspension of the troughs may be effected in a variety of ways. As herein shown it is done by tubular rods 90 *L L*, attached to the ceiling above. Only two of these rods are shown; but practically they 95 will be arranged at suitable distances along the troughs, which are provided with flanged edges resting upon long slender horizontal beams *M*, located between the said rods and attached to clips *N*, secured to the same. 100 Hollow distributing-drums *O*, made of light sheet metal, are journaled in quadrangular frames *P*, setting into the troughs and having flanged ends *Q*, adapting them to rest upon

the edges of the troughs and to be moved horizontally upon the same when desired to clean the troughs or secure more convenient access to those parts of the apparatus which lie adjacent to the drums. A horizontal strip-controller, (see Fig. 7,) provided for each drum, and extending transversely across the trough in which the drum is located, consists of a small roller R and two parallel arms S S, extended at their forward ends and provided with eyes. The drums and frames of the upper and lower troughs are arranged in the same vertical planes, so as to co-operate with each other, as will be described hereinafter. 15 Cords T, coupling the corresponding upper and lower controllers through the eyes of the same, are provided for lifting them sufficiently to cause their rollers R to strip any excess of adhesive material from the paper 20 or lift it entirely above the drums. The controllers of the upper trough are pivoted to strip-controller shafts U, carrying small rollers V, and attached to clips W, embracing the suspension-rod L, while the corresponding 25 strip-controllers of the lower trough are pivoted to shafts X, secured to roller-arms Y, clipped to the lower ends of the said suspension-rods.

The stock-coils Z, which extend parallel 30 with the drums and troughs, are supported in vertical racks A', located on opposite sides of the upper trough and suspended from rack-shafts B', supported by rack-frames C', secured to the suspension-rods. Each coil (see 35 Fig. 12) is mounted upon a cranked shaft D', carrying two tapering plugs E' E', which respectively enter the opposite ends of the central opening of the coil, the inner plug—that is, the plug nearest to the cranked end of the 40 shaft—being slotted to receive a pin F', carried thereby, whereby such plug is locked upon the shaft, with which the coil will then rotate. The outer ends of these plugs project beyond the ends of the coil and so protect the edges thereof against injury by chafing 45 against the racks A', in which the shaft is suspended. If desired, the racks may be set up to have frictional contact with the said ends of the plugs, so as to control the unwinding 50 of the coil. Each of the said racks is provided with a vertical series of slots, whereby the stock-coils may be shifted and lifted as they are unwound and decrease in size, the full coils being placed with their cranks in 55 the lower slots, as shown in the drawings, in which, however, the coils are shown as partly unwound. Roller-frames G', located above the upper trough, carry central rollers II' and I', situated one above the other, and two pairs 60 of flying rollers J' J', of which one pair is located on one side of the trough and the other on the opposite side thereof. Rollers K', carried by the roller-arms Y aforesaid, are located on opposite sides of the lower trough 65 and coat with the drum therein. Delivering-rollers L', carried by long arms M', secured to

the upper ends of the suspension-rods and extended therefrom out over the edges of the work-table, deliver the paper thereto. The said suspension-rods L and the several parts 70 attached thereto, inclusive of the racks and frames constituting the roll-carriers, form a supporting-frame of the machine, these frames being duplicated along the troughs thereof according to its capacity. The said suspension-rods and the frames, arms, and racks attached to them form, broadly speaking, suspension-frames adapted to be hung from their upper ends and to support the troughs, being extended transversely thereto to carry the 80 stock-coils and the uncoiled paper and to deliver the same to the table below. So, too, the rollers, although differently named to facilitate distinguishing them apart, are all carrying-rollers in their common function of holding 85 the uncoiled paper in a state of suspension. A standard N', firmly secured to the said table, carries a horizontal tapering spindle O', having a pin P' in its end and carrying the expandible box-former, which is composed 90 of two corresponding acute-angle pieces Q' and two corresponding obtuse-angle pieces R', constructed and arranged to be fitted together to form a rectangular body and tensioned and rabbeted, so as to be relatively separated without losing the integrity of their arrangement. The inner ends of these pieces are cut away, as at S', to form a circular opening, adapting the former to be slipped over the spindle before mentioned, while their opposite faces are grooved, as at T', to receive the rubber rings U', which draw the pieces together after their expansion upon the inner end of the said spindle, which is larger than the outer end thereof. 95

A graduated measuring-board V', having its upper end provided with long hooks W', and thereby adapted to be suspended from the shaft of a delivering-roller, is adapted in length to rest upon the table or extend below 100 the same. This board is provided with a central longitudinal slot X', for the vertical adjustment of a block forming a stop-gage Y' and the similar adjustment of a block or platform forming a cut-off gage Z', carrying a 105 pair of shears A², arranged horizontally, so that the strip will pass between their blades in position to be severed by them. A spring B², placed between the shear-handles, serves to keep the blades normally apart. A cord 110 C² and pulley D², attached to the said handles, is provided for operating the shears conveniently from the table. A roller E², mounted in a handle F², is provided for developing the corners of the green forms, be they box-bodies 115 or box-covers, when the same are still upon the box-former.

Depending fingers I² I², secured to the strip-controller shafts X', respectively, on opposite sides of the strip, are provided for keeping 120 the same in place upon the lower drums. Glasses J² J², inserted into the ends of the

troughs, (see Fig. 2,) are provided for enabling the level of the material therein to be easily watched.

Having fully described my improved apparatus, I will now set forth the method of its operation in the formation of a box-body and then in the covering of the same.

Referring now to Figs. 1 and 3 of the drawings, the strip G^2 , which is a heavy quality of paper, is led from the stock-roll over the drum of the upper trough, which is preferably filled with a thin solution of glue or sizing, the same being applied to the under surface of the strip which passes down over the stripping-roller of the strip-controller and under the roller mounted on the adjacent strip-controller shaft. From this roller the strip passes up and over the roller H' , thence down over that pair of flying rollers $J' J'$ located adjacent to the stock-roll, thence down to and under the adjacent roller K' and over the corresponding drum of the lower trough, which is filled with glue, the same being applied to the strip which has been prepared to receive it by the previous application of sizing. The glued strip then passes over the roller of the strip-controller of the drum just mentioned and under the adjacent roller K' , thence up and over the other pair of flying rollers $J' J'$, thence over the roller I' , and thence to the delivering-roller L' , located on the side of the apparatus on which the stock-roll is located. From the delivering-roller the strip drops down over the box-former with its glued side 35 out or uppermost. An operative standing by the same seizes the end of the strip and places it upon the former, which is now manually rotated until the required number of thicknesses of paper have been secured upon it, when the strip, being damp, is broken off by hand or cut with a knife. This done, the former is slipped along to the outer and smaller end of the forming-spindle, where it is contracted by the rubber rings which hold 45 its parts together, thereby leaving the box-body formed upon it free to be removed. Before this is done, however, the body has secured to it a straw-board box-bottom, (or cover-top, when covers are being made,) which 50 is supported meanwhile by the pin in the end of the spindle, those edges of the strip adjacent to the said box-bottom being lapped over upon the same. The green box-body is now removed from the former and the operation 55 repeated, every operation reeling more paper from the roll and drawing it over the drums. The said box-body has now to be covered with a paper of lighter weight and perhaps fancy coloring. For this covering 60 operation attention is called to Figs. 2 and 4 of the drawings, in which the strip H^2 from the stock-roll follows the exact course already pointed out, and is eventually delivered with its gummed side out to the measuring-board, 65 the stop-gage and cut-off gage whereof are set according to the length of the sections to be cut off. If the strips are to be used in cov-

ering the boxes formed as described, they are adapted in length thereto. The attendant standing by this board pulls the strip down 70 to the stop-gage, and then either applies the article to be covered to it and rolls it over on the board and then pulls the cord, causing the shears to cut it off, or measures and cuts off strip after strip, the strips so obtained being then handed to another attendant, who uses them. It may be noted that in preparing the covering-strip for use less gum 75 is applied to it, this being controlled by the strip-controllers.

All of this apparatus being suspended above the work-table, a great economy of space is secured, together with a convenience greatly facilitating the work, which may be done on either or both sides of the table and in any desired alternation by simply reversing the direction of the strips. The machine may be used in whole or in part with equally good results and as economically one way as the other. By first applying a sizing to the 90 strips and then holding them for a time before applying the glue the paper is admirably tempered to receive the glue, which is then applied evenly, and when applied remains upon the surface, instead of at once being 95 taken up by the paper, as occurs when glue is applied to dry paper, which at once absorbs the water in it. Then, again, in case the glue is not well applied when the paper goes over the first drum, the chances are that spots not 100 touched then will be when in a generally moistened, and hence more pliant, state it passes over the second drum. The paper, being suspended or held some time before its 105 delivery for use, becomes so well tempered as to work better and with less wrinkling than under old methods of handling and treating it. Under this invention also, and because each trough contains a great amount of adhesive material, which is therefore taken up 110 and reduced in level very slowly, the degree to which the drums are immersed in such material is maintained virtually without fluctuation—obviously securing a more uniform distribution—whereas in apparatus containing only a small supply of glue its level is 115 changed rapidly, so that the drums will be immersed more at one time than at another, and hence effect an unequal distribution of the adhesive. Again, under this invention the 120 adhesive materials are easily and economically handled. If desired, they can at any time be drawn off from the troughs for changing them for different material or to permit the troughs to be washed out. The adaptation of the drum-frames to be moved lengthwise of the troughs favors an easy care of the 125 apparatus. The amount of adhesive material applied to the paper is readily controlled by raising or lowering the strip-controllers by 130 means of the coupling-cord. When the controllers are lifted, the rollers carried at their forward ends operate to strip the adhesive from the paper back into the troughs, the

amount of adhesive so removed being proportional to the lifting of the controllers. If desired, the controllers may be lifted so as to clear the paper of the drums altogether. In 5 this way the gummed paper may be used up clean and waste avoided, the length of paper passing through without being gummed being cut off and afterward put through in contact with the rolls.

10 It is apparent that in carrying out my invention some changes in the construction and arrangement of parts herein shown and described may be made. I would therefore have it understood that I do not limit myself 15 to such construction and arrangement, but hold myself at liberty to make such changes and alterations as fairly fall within the spirit and scope of my invention.

Having fully described my invention, what I 20 claim as new, and desire to secure by Letters Patent, is—

1. In a machine for making paper boxes, the combination, with a supporting-frame, of a long horizontal trough mounted therein, a distributing-drum mounted in the trough and extending parallel therewith, and stock and carrying rolls extending parallel with the trough and drums and mounted in the frame, which is thereto extended transversely to the trough 25 and to the general direction of the machine, the trough being adapted to receive a series of drums, each of which will have its complement of rolls, whereby several stock-strips may be passed transversely across the trough 30 and delivered from the sides thereof, substantially as described.

2. In a machine for making paper boxes, the combination, with upright suspension-rods adapted to be supported from their upper 40 ends, of a long trough suspended from the said rods, a distributing-drum located in the trough and extending parallel therewith, roll-carriers attached to the said rods and extending out on opposite sides of the trough at a 45 right angle to the length thereof, and stock and carrying rolls mounted in the said roll-carriers and extending parallel with the trough and drum, the stock-strip being passed and repassed transversely across the trough 50 and delivered from one side of the same, substantially as described.

3. In a machine for making paper boxes, the combination, with a supporting-frame having laterally-extending roll-carriers, of two long 55 troughs arranged vertically one above the other and suspended in the said frame, a distributing-drum located in each of the said troughs and extending parallel therewith, stock and carrying rolls mounted in the said 60 roll-carriers, which project out on opposite sides of the trough and arranged to pass the stock from one drum to the other, the stock being passed and repassed transversely over the troughs and delivered from one side of them, substantially as described.

4. In a machine for making paper boxes, the combination, with a long horizontal trough,

of a quadrangular drum-frame supported upon the upper edges thereof and adapted to be freely moved endwise thereupon, a drum 70 mounted in the frame and extending parallel with the trough, and means for supporting a stock-roll and conducting the stock transversely across the trough and over the drum, substantially as described.

5. In a machine for making paper boxes, the combination, with a trough, of a drum mounted therein and extending parallel therewith, a strip-controller consisting of two long 80 pivotal arms and a drum mounted in them and located in position for the stock-strip to pass over it, and means for lifting the said controller, whereby the stock-strip may be raised up to clear the drum or to make greater or less contact therewith, substantially as de- 85 scribed.

6. In a machine for making paper boxes, the combination, with a trough, of a drum mounted therein and extending parallel therewith, a vertically-adjustable strip-controller 90 adapted to engage the under side of the stock-strip, and means for adjusting the said controller and holding it in its adjustment, substantially as described.

7. In a machine for making paper boxes, the combination, with two long horizontal troughs, of a drum located in each trough and extending parallel therewith, a strip-controller located over each drum and extending transversely across the troughs thereof, and a 100 coupler connecting the corresponding strip-controllers of the two troughs, substantially as set forth.

8. In a machine for making paper boxes, the combination, with a box-former composed of 105 four angled pieces having their corresponding faces rabbeted and tenoned, and each segmentally grooved at each end to form, when assembled, two circular grooves, of elastic rings located in the said circular grooves, and 110 a stationary forming-spindle upon which the box-former is manually moved, substantially as set forth.

9. In a machine for making paper boxes, the combination, with a frame adapted to be suspended from its upper end over a work-table, of a horizontal trough mounted in the said frame, a drum located in the trough and extending parallel therewith, carrying-rollers extending parallel with the trough and drum 120 mounted in the frame, which is thereto extended transversely to the trough, and a measuring-board extending between the said rollers and the work-table below the frame and provided with a gage, substantially as set 125 forth.

10. In a machine for making paper boxes, the combination, with a frame suspended over a work-table, of a horizontal trough suspended in the said frame, a drum located in the 130 trough and extending parallel therewith, carrying-rollers mounted in the frame and extending parallel with the trough and drum, and a measuring-board suspended from its

upper end extending down to the work-table from the rolls and carrying one or more gages and a cutting-off device, substantially as set forth.

5 11. In a machine for making paper boxes, the combination, with a trough and carrying-rollers suspended over a work-table, of a measuring-board suspended from its upper end and extending from the rollers down to the table, shears extending horizontally across the said board and adapted to be vertically adjusted thereupon, and means for manually operating them, substantially as set forth.

12. In a machine for making paper boxes, the combination, with a frame adapted to be suspended from its upper end over a work-

table, and consisting of vertical suspension-rods and lateral arms attached thereto, of a horizontal trough mounted in the said frame, a drum mounted in the trough and extending parallel therewith, carrying-rollers mounted in the frame and extending parallel with the trough and drum, and forming and measuring devices, substantially as set forth. 20

In testimony whereof I have signed this 25 specification in the presence of two subscribing witnesses.

JULIUS H. BITTERLICH.
